(57) CLAIM

I claim the ornamental design for a card holder for a portable device, as shown and described.

DESCRIPTION

FIG. 1 shows a left side view a card holder according to the invention;

FIG. 2 shows a top view of the holder of FIG. 1;

FIG. 3 shows a bottom view of the holder of FIG. 1;

FIG. 4 shows a front side view of the holder of FIG. 1;

FIG. 5 shows a right side view of the holder of FIG. 1; and,

FIG. 6 shows a back side view of the holder of FIG. 1.

The broken lines showing portions of the holder are for the purposes of illustrating environment and forms no part of the claimed design.
